UNITED STATES PATENT OFFICE.

HERBERT M. SCOTT, OF PORTSMOUTH, VIRGINIA.

SAFETY LIGHTING TORCH.

Application filed May 22, 1922. Serial No. 562,740.

To all whom it may concern:

Be it known that I, HERBERT M. SCOTT, a citizen of the United States, residing at Portsmouth, in the county of Norfolk and State of Virginia, have invented a new and useful Safety Lighting Torch, of which the following is a specification.

By way of explanation it may be stated that disastrous fires often have occurred, in steam vessels, by reason of the fact that it is necessary to carry a lighted torch from place to place, for the purpose of lighting the boiler burners of the vessel.

The foregoing being understood, it is one object of the invention to provide a torch which may be extinguished readily, and be lighted without difficulty, there being no occasion for carrying a lighted torch from place to place. Although the device is adapted peculiarly to be used on vessels, for the purpose stated, it is by no means confined, in its application, to such a use.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention; Figure 2 is a longitudinal section wherein parts appear in elevation; Figure 3 is a transverse section on the line 3—3 of Figure 2; Figure 4 is a fragmental longitudinal section showing a modified form of the invention; Figure 5 is a transverse section on the line 5—5 of Figure 4.

Referring to Figures 1, 2 and 3, the device is shown as including a tubular body 1, provided at one end with an enlarged casing 2 which may be considered as part of the body. A bayonet slot 3 is fashioned in the body 1 and includes a transverse extension 4. At its inner end, the body 1 is sur-

rounded by a grip 5 which is secured to the body, the grip being equipped in its outer end with notches 6. A guide 7 is inserted into the inner end of the body 1 and is held therein by securing elements 8 received in the notches 6 of the grip 5.

A plunger 9 is mounted for reciprocation in the guide 7 and extends within the body 1, the plunger being provided at its rear end with a handle 10. Intermediate its ends, the plunger 9 carries a lug 11, disposed within the body 1. A retractile spring 12 is housed within the body 1 and is coiled about the plunger 9, one end of the spring being mounted in the lug 11 and the other end of the spring being extended through the guide 7 and being bent to engage the same, as shown at 14, the guide having a seat 15 in its outer end, through which the extremity of the spring 12 passes. The plunger 9 has lateral projection 16, mounted to move in the bayonet slot 3 of the body 1. Adjacent to its outer end, the plunger 9 carries spaced disks 17 and 18, between which is located a mass of absorbent material 19, constituting a fuel carrier.

When the projection 16 on the plunger 9 is disengaged from the extension 4 of the bayonet slot 3, the spring 12 tends to retract the plunger 9, so that the fuel carrier 19 is housed completely in the casing 2 of the body 1. The operator, however, may advance the plunger 9, by means of the handle 10, until the fuel carrier 19 projects beyond the casing 2, as shown in Figure 2, the disk 17 remaining in the casing 2, to serve as a guide for the plunger. When the plunger 9 is advanced, as shown in Figure 2, the spring 12 is put under tension. If the plunger 9 be rotated slightly the projection 16 will be engaged in the extension 4 of the bayonet slot 3, and, thus, the parts will be held in the position of Figure 2, against the retracting action of the spring 12. The absorbent material 19, being saturated with fuel, may be ignited, and the device may be used as a torch, for lighting burners or for any other purpose. If rotation be imparted to the plunger 9, the projection 16 will move out of the extension 4 of the bayonet slot 3, whereupon the spring 12 will react upon the plunger 9, retracting the plunger, and drawing the absorbent material 19 into the cas-

ing 2, the flame existing at the part 19 being extinguished. The general construction of the device, obviously, is such that the flame of the torch may be put out by a simple movement, it being unnecessary to tread out the flame or smother it by any other operation likely to produce a fire.

5 The modification disclosed in Figures 4 and 5 embodies a means whereby the torch 10 may be lighted electrically. The bayonet slot 3, the projection 16, the spring 12, and attendant parts, are used, as hereinbefore explained.

15 The device as disclosed in Figures 4 and 5 includes a tubular body 20 carrying an enlarged casing 21. The hollow plunger appears at 22, and the handle at 40. A disk 23 is mounted on the plunger 22 and the plunger carries a spider 24. A mass of absorbent material 25 constituting a fuel carrier, surrounds the plunger 23 and is located 20 between the disk 23 and the spider 24. A closure 27 is mounted on the outer end of the plunger 22 and substantially fills the casing 21 transversely when the plunger 22 is retracted, as shown in Figure 4. The closure 27 may be held on the plunger 22 in any desired way. If preferred, a plug 26 may be mounted in the outer end of the 25 plunger, a securing member 28 passing through the closure and engaging the plug. The plunger 22 carries terminals 30, disposed between the spider 24 and the closure 27, the terminals having curved ends 31 extended into close relation to each other as shown in Figure 5, so that a spark may jump therebetween. The terminals 30 are interposed in a circuit 32, extended through the hollow plunger 22. A switch 33 is mounted on any 30 desired portion of the plunger 22, the switch being placed adjacent to the handle 40 if desired, and being interposed in the circuit 32. The numeral 34 marks a source of electrical energy, disposed in the circuit 32.

45 When the plunger 22 is advanced, as shown in connection with the plunger 9 of Figure 2, the circuit 32 may be closed through the instrumentality of the switch 33, whereupon a spark will jump between the ends 31 of the terminals 30. Since the spider 24 is of open work construction, the fuel in the absorbent material 25 will supply a gas which will be ignited readily by the spark, the flame being transferred to the fuel in the absorbent material 25 and the torch being used in the way hereinbefore explained in connection with the torch shown in Figures 1 and 2. When the occasion for the use of the torch has passed, the plunger 50 22 is retracted in the way hereinbefore set forth, the closure 27 cooperating with the end of the casing 21 to extinguish the flame.

What is claimed is:

1. A torch comprising a tubular body having an imperforate portion at one end and

provided intermediate its ends with a bayonet slot having a lateral extension, a plunger and a fuel-carrier mounted on the plunger, the plunger and the carrier being 70 slideable in the body to permit the carrier to be advanced and retracted with respect to the other end of the body, the plunger having a projection; a retractile spring within the body and connected at one end to the plunger, and means for connecting the retractile spring to the first specified end of the body, the spring being housed completely in said imperforate portion of the body when the spring is expanded and when the projection is received in the extension 80 of the bayonet slot.

2. A torch comprising a tubular body, a guide in one end of the body, a plunger slideable in the guide, a retractile spring in the body, one end of the spring being connected 85 to the guide, and the other end of the spring being connected to the plunger, a fuel-carrier mounted on the plunger for advancement with respect to the other end of the body, and latch mechanism for holding the plunger and the carrier advanced, against the retractile effort of the spring.

3. A torch comprising a tubular body, a guide on one end of the body, a plunger slideable in the guide, a retractile spring in the body, one end of the spring being connected to the guide, and the other end of the spring being connected to the plunger, a fuel-carrier mounted on the plunger, for advancement with respect to the other end of the 100 body, latch mechanism for holding the plunger and the carrier advanced, against the retractile effort of the spring, a securing device holding the guide on the body, and a grip on the body, the grip having an opening giving access to the securing element.

4. A torch comprising a tubular body, a hollow plunger slideable in the body, a fuel-carrier on the plunger and movable into and out of the body, cooperating terminals mounted on the plunger and located in advance of the carrier, and conductors assembled with the terminals and extended backwardly through the hollow plunger.

5. A torch comprising a body, a hollow plunger slideable in the body, a fuel-carrier on the plunger, a closure for the body, the closure being spaced from the carrier and being mounted on the plunger, terminals mounted on the plunger and disposed between the closure and the carrier and conductors extended backwardly from the terminals through the plunger.

6. A torch comprising a body, a plunger slideable in the body, a fuel-carrier on the plunger, a closure for the body, the closure being spaced from the carrier and being mounted on the plunger, and an ignition means for the fuel-carrier, the ignition means comprising a part disposed between 125

the carrier and the closure and mounted on the plunger, and constituting means whereby the ignition is communicated to the carrier, said part being housed within the body, 5 when the closure is in place with respect to the body.

In testimony that I claim the foregoing

as my own, I have hereto affixed my signature in the presence of two witnesses.

HERBERT M. SCOTT.
